ROTARY TYPE CAN OPENER

Robert E. McLean, Fort Benning, Ga.

Application October 16, 1942, Serial No. 462,302

20 Claims. (Cl. 30—9)

This invention relates generally to the class of implements or tools designed for the opening of sealed metallic receptacles, such as tin cans and the like, and the present application is based upon and sets forth certain novel improvements over the structures disclosed in my prior Patents No. 2,294,507 of September 1, 1942, and No. 2,287,442 of June 23, 1942, upon which last-mentioned patent the matter of the first-mentioned patent is based, and over which it sets forth novel improvements.

A particular object of the present invention is to provide certain embodiments of a novel type of escapement mechanism which may be employed in connection with the several embodiments of my improved rotary can opener which is set forth in my prior patents above referred to.

The openers of my prior patents and my present application employ in association with a cutter and a can rim engaging and driving wheel which is rotated by means of a crank, a cam means for effecting relative movement between the cutter and the driving wheel, and mechanism for cooperatively coupling the crank with the means for effecting relative movement between the wheel and cutter when the crank is turned in a desired direction so as to effect shifting of the can toward the cutter to bring about a penetration of the can head by the cutter and the cutting out of the head or the shifting of the can away from the cutter after such head has been cut away.

The operative coupling established between the crank handle and the said movement effecting means is, as stated, intermittently operated upon the turning of the crank, and in the present case several forms or embodiments are shown and described of a novel escapement mechanism carried upon the body of the implement, whereby the desired coupling of the handle with the means for producing the stated relative movement between the wheel and cutter is accomplished until a limit of such movement is reached, whereupon such coupling will be automatically released or disengaged to permit continued movement of the crank for the operation of the driving wheel, without affecting further the stated movement effecting means.

Another object of the invention is to provide a novel escapement mechanism for a rotary type can opener, as above set forth, wherein the several movable elements of the escapement are all mounted upon the body of the opener and are effectively housed or shielded with the exception

of a small portion only which cooperates with the crank handle.

Still another object of the invention is to provide an escapement mechanism by which, upon rotation of the crank of the opener, the desired relative movement between the driving wheel and knife is effected, wherein the several movable parts are not only compactly housed upon the body of the implement, but in which such movable parts are constructed and coupled together in a manner to give a strong and sturdy construction and in a manner to effect the quick disconnection of the crank handle from the stated movement effecting means when the desired limit of such movement has been reached.

The invention will be best understood from a consideration of the following detailed description taken in connection with the accompanying drawings, it being understood, however, that the invention is not to be considered as limited by the specific illustration or description but that such illustration and description constitute a preferred embodiment of the invention.

In the drawings:

25 Figure 1 is a view, partly in front elevation and partly in longitudinal section, of a rotary type can opener showing as a part thereof one embodiment of the improved escapement mechanism.

30 Figure 2 is a view in side elevation and upon an enlarged scale of the escapement mechanism oscillated counter-clockwise to the position which it assumes when the cutting knife and driving roller have been separated and showing the position of the crank handle at the moment of connection between the same and the escapement as the handle is being turned clockwise.

35 Figure 3 is a view in side elevation and upon an enlarged scale of the lower portion of the structure shown in Figure 1, showing the position of the parts immediately prior to the operation of the escapement, a portion of the structure being in section.

40 Figure 4 is a view similar to Figure 3 but showing in dotted outline the positions of the parts of the escapement mechanism immediately following the release or disconnection of the crank handle therefrom.

45 Figure 5 illustrates in front elevation another embodiment of escapement mechanism, the upper part of the can opener not being shown.

50 Figure 6 is a view in side elevation and upon an enlarged scale of the embodiment shown in Figure 5, showing the positions of the parts at

the moment of disconnection of the elements of the escapement.

Figure 7 is a view in front elevation of another embodiment of escapement, the other parts of the opener not being illustrated.

Figure 8 is a view in side elevation of the escapement shown in Figure 7, a portion of the structure being broken away.

Figure 9 is a view in front elevation of still another embodiment of escapement, other parts of the opener not being shown.

Figure 10 is a view in side elevation of the escapement shown in Figure 9, parts being broken away.

Figure 11 is a view in front elevation of still another embodiment of the escapement, other parts of the opener structure not being shown.

Figure 12 is a view in side elevation of the escapement shown in Figure 11, parts being broken away.

Figure 13 is a view in side elevation of a hand supported type of rotary can opener showing another embodiment of escapement mechanism.

Figure 14 is a view in elevation of the thrust mechanism side of the form of opener shown in Figure 13.

Figure 15 is a view in front elevation of the opener shown in Figure 13.

Figure 16 is a view in top plan of the opener.

Figure 17 is a vertical longitudinal section taken substantially upon the line 17-17 of Figure 13.

Figure 18 is a view in elevation of the thrust mechanism side of the opener shown in Figure 14, showing such mechanism shifted to the position in which the driving wheel is lowered.

Figure 19 is a view in top plan of still another form or embodiment of the hand supported opener and escapement mechanism therefor.

Figure 20 is a view in side elevation of the form of opener shown in Figure 19.

Figure 21 is a view, partly in front elevation and partly in vertical section, of a further embodiment of my can opener which is directed particularly to a novel spring supported bearing for the eccentric wheel, which may be used in place of the spring arms shown in the instruments of my prior patents and in Figures 1 and 3 to 6 of the present application.

Figure 22 is a view in elevation of the upper portion of the handle side of the implement shown in Figure 21, the shaft for actuating the driving wheel being in section and the handle removed, this view illustrating a modified form of escapement based upon the form illustrated in Figures 11 and 12.

Figure 23 is a view in elevation of the upper portion of the implement upon the opposite side from the handle, showing particularly the mounting for the cutting blade.

Figure 24 is a view in top plan of the body plate and knife carrying portion only of the implement shown in Figure 21.

Figure 25 is a view partly in side elevation and partly in section of the carrier for the spring supported eccentric wheel bearing.

Figure 26 is a sectional view on the line 26-26 of Figure 25.

Figure 27 is a view in perspective of the bearing and spring carrying unit per se, the bearing and springs being removed therefrom.

Figure 28 illustrates the application to the present improved eccentric wheel spring supported bearing of the form of escapement illustrated in Figures 13 to 18 of the present applica-

tion, and in Figures 12 to 15 of the structure in Patent No. 2,287,442.

Figure 29 illustrates the structure of Figure 28 as seen when viewing the instrument in front elevation.

In Figure 1 a complete rotary type can opener is illustrated, the same being viewed in front elevation and the top portion thereof being in section. The upper part of this opener is illustrated and particularly described in a prior application and there is associated with this cutter one embodiment of the present improved escapement. This view of the complete implement is given and will be described so that the application of the escapement may be clearly understood, but in the illustration and description of the embodiments shown in Figures 5 to 12 inclusive the entire implement is not shown but only that portion of the body thereof upon which the escapement is mounted.

It will be understood that with these several embodiments of the escapement, any of the different forms of top construction illustrated in my prior Patents 2,287,442 and 2,294,507 previously referred to, might be employed.

In Figure 1 and in each of the subsequent figures the body of the implement is indicated generally by the numeral 1. This body is in the form of a plate of suitable width and length and is secured at one end to a suitable supporting bracket 2 by which it is maintained in upright position. Between this supporting bracket and the body 1 is secured a plate 3, from the rear edge of which there curves upwardly and forwardly the integral flat spring arm 4 which lies against one side of the plate body 1, as shown in Figure 1.

At its upper end the plate body 1 is laterally offset to form a bearing shoulder 5 and from this offset portion there extends obliquely upwardly the straight extension 6 which at its upper end merges with the short transverse portion 7, and this in turn merges with the downwardly extending terminal portion 8 which is in spaced parallel relation with the portion 6. These portions 6, 7 and 8 form the head of the implement and the portion 8 has an opening 9 formed therethrough which is coaxial with a coacting opening 10 which is in the portion 6.

Extending through the opening 9 is a bearing sleeve 11 which has a flange 12 at its upper end which limits its longitudinal movement through the opening. At its opposite end this sleeve extends into and terminates in the opening 10 and it is transversely flattened, at 13, to coact with the correspondingly straight or flattened portion of the opening 10, whereby the sleeve is held against turning.

Extending through the bearing sleeve 11 is a shaft 14 having the head 15 which, at the upper end of the shaft, bears against the sleeve flange 12 while at its other end, which extends a substantial distance beyond the head portion 6, it is reduced and threaded, as indicated at 16, to receive a rotary type cutter 17.

Rotatably mounted upon the shaft 14 and maintained in position against the adjacent side of the portion 6 of the head by the cutter 17 is an idler roller 18 against which the top edge of the flange of a can is pressed or forced by the herein-after described driving wheel, in the operation of the implement.

Below the shoulder 5 the body plate 1 has an elongated opening 19 cut therein and extending transversely of the plate through this opening is

a sleeve 20 which is encircled by the integral collar 21. This collar fits snugly in the elongated opening 18 and is designed to rotate therein and to have movement longitudinally therein.

Upon the end of the sleeve 20 nearest the cutter 17 there is secured an eccentric wheel 22 which is in peripheral contact with and is retained between the shoulder 5 and the spring 4.

Extending through and secured in the sleeve 20 is a bearing sleeve 23 through which extends the crank shaft 24. The shaft 24 has secured upon that end nearest the cutting wheel 17, a can flange engaging driving wheel 25 which is arranged with its periphery in the vertical plane of the lowest part of the idler wheel 18.

The structure thus far described is all set forth and particularly claimed in my companion application and, as is set forth therein, when turning movement is given the eccentric wheel 22 in one direction the driving wheel 25 is caused to move upwardly toward the idler 18 and, if in engagement with the lower edge of a can flange during such movement, the can will be forced upwardly so that the edge of the cutting wheel 17 will be driven through the head of the can and the can flange will be gripped between the driving wheel 25 and the idler roller and continued rotation of the driving wheel will cause the can to be turned and the head to be cut out. Upon reverse rotation of the shaft 24 to turn the eccentric wheel 22 the driving wheel 25 will be lowered so that the can may be readily removed from the implement.

The numeral 26 designates the operating crank handle which is secured at one end to the shaft 24, and the desired operative connection between this crank and the eccentric wheel is established by means of the different embodiments of the mechanism about to be described.

The handle 26 carries upon the side nearest the body plate 1 a trip finger 27 which is here illustrated as being a part of a plate body 28 which is secured to the side of the handle, although obviously it may be joined directly to the crank handle without forming a part of the plate shown. This trip finger 27 coats with an escapement mechanism which is indicated generally or as a whole by the numeral 29 and which is interposed between the body 1 and the handle 26, as clearly shown in Figure 1.

The escapement 29 comprises a plate 30 which is parallel with the body plate 1 and which has at its front, top and back edges the inwardly extending flanges 31, 32 and 33, respectively. The front flange 31 has the opening or recess 34 therein for the purpose hereinafter described.

Extending upwardly from the inner edge of the top flange 32, in close proximity to the body 1, is an ear 35 through which extend the sleeve 20, the bearing sleeve 23 and the shaft 24 and, as shown in Figure 1, the sleeve 20 is fixed to this ear so that rotary movement may be imparted to the sleeve 20 about the bearing sleeve 23 by the swinging of the escapement mechanism plate 30.

Secured to the plate 30 and disposed upon the inner side thereof, which is the side nearest the body plate 1, is a pivot stud 36. Pivotaly supported upon this stud 36 is a trigger arm 37 which extends downwardly below the arcuate lower edge of the plate 30, as is clearly shown in Figure 3.

The trip finger 27 is suitably positioned upon the crank handle 26 to move lengthwise of but in spaced relation with the arcuate lower edge of the plate 30 so as to strike the sides of the trigger. These opposite sides of the trigger are angled with respect to the length of the trigger, 75

as indicated at 38, so that a flat contact will be made between the trip finger and the trigger when the crank handle is turned either clockwise or counterclockwise.

At its upper end the trigger has the right angularly extending forwardly directed arm 39 which, adjacent its free end, is offset from the plate 30 to receive one end of the part 40 of a snap link 41. This end of the element 40 is pivotally coupled to the arm 39 by the pin 42.

Adjacent the top of the plate 30 and at the forward edge thereof is a pivot 43 to which the other end of the snap link 41 is pivotally connected through the medium of the element 44, and the elements 40 and 44 are pivotally joined together by the pin 45 which, when the snap link is substantially straight, as shown in Figures 2 and 3, is opposite the opening 34 in the flange 31. One of the elements, here shown as the element 40, is extended slightly beyond the pivot 45 to form the stop tall piece 46 which comes into engagement with the top flange 32, as illustrated in Figure 4, when the snap link is broken to limit the relative movement of the elements.

The body plate 1 carries a trip pin 47 which is positioned to enter the opening or recess 34 when the escapement mechanism is swung forwardly, and engage the snap link 41 at its transverse center, as shown in Figure 3, to effect the breaking of the link.

In the operation of the implement as just described, when the eccentric wheel 22 has been rotated counter-clockwise to the limit of its movement in this direction the driving wheel 25 will be moved down away from the cutter 17 so that the rim flange of a can may be readily inserted to engage over the driving wheel in the manner well known in connection with can openers of the type set forth. The escapement mechanism 29 will then be in the rearwardly swung position in which it is shown in Figure 2. The movement of the escapement to this rearward position may be accomplished by imparting counter-clockwise turning movement to the handle 26 so as to bring the finger 27 around against the front face 38 of the trigger 37. At the same time the snap link will be straightened, as shown in Figure 2, and the trigger 37 will be swung to the limit of its movement toward the rear flange 33 of the plate 30.

After the can has been placed in position in a known manner so that the flange rests upon the top of the driving wheel 25, the crank 26 is swung around clockwise to the position in which it is shown in Figure 2 so that the trip finger 27 will be brought to bear against the back edge 38 of the trigger. The application of force to the crank will then cause the mechanism to swing downwardly and forwardly, causing the eccentric wheel 22 to be turned so as to raise the driving wheel and the can and force the head of the can against the edge of the cutter 17 by which the head is penetrated. When the can has been raised so that the cutter is forced through the head and the can rim flange is secured between the driving wheel 25 and the idler 18 the escapement mechanism will be approximately in the position shown in Figure 3 with the trip 47 bearing against the central part of the snap link 41. The continued application of force to the crank will cause the trip to break the snap link, as shown in dotted outline in Figure 4, thus swinging the trigger upwardly so that the finger 27 may slip off of the lower end of the trigger and pass the same. This will then permit the con-

tinued clockwise rotation of the crank handle for the complete removal of the can head.

In the embodiment of the escapement shown in Figures 5 and 6 the plate body upon which the escapement is shown as being mounted is indicated generally by the numeral 1^a, while the driving wheel is designated 25^a, the eccentric wheel is designated 22^a and the spring upon which it bears and the shoulder overlying it and which it contacts are designated 4^a and 5^a, respectively. The crank handle is designated 26^a and the trip finger carried by the crank handle is designated 27^a.

The escapement unit as a whole is indicated by the reference character 29^a. This escapement unit comprises the plate body 48 which has the inturned top flange 49, from the inner edge of which extends upwardly the ear 50 which is operatively coupled with the eccentric wheel in the same manner as the ear 35 of the mechanism shown in Figure 3. The rear edge of the plate body 48 is bordered by the inwardly extending flange 51 which is directed toward the adjacent body 1^a and which terminates at the arcuate lower edge of the plate body, as shown in Figure 6. The forward edge of the plate 48 also has an inwardly extending flange which is indicated by the numeral 52 and which extends from the arcuate lower edge of the plate upwardly toward but terminates short of the top flange 49, thus leaving the recess or entrance opening 53.

Adjacent the lower edge of the plate 48 and near the back flange 51, the plate carries a pivoted stud 54 upon which is oscillatably mounted the trigger 55 which extends below the arcuate lower edge of the plate and which has the oblique front and rear contact edges 56, for engagement by the trip finger 27^a.

Extending forwardly and substantially at right angles to the length of the trigger 55 and from the pivoted end of the trigger is a bill 57 which coacts with the downwardly and forwardly curving lower end portion 58 of a latch arm 59. This latch arm 59 is pivotally supported upon the stud 60 which is carried by the plate body 48, as shown in Figure 6, its connection with the pivot stud being substantially midway between its ends and the upper end portion 61 is somewhat heavier than the lower portion 58 and extends straight upwardly across the opening 53. Secured to the body plate 1^a is the trip pin or arm 47^a which is so positioned that when the escapement mechanism is swung down and slightly forwardly, as shown in Figure 6, it will enter the opening or recess 53 and strike the upper end portion 61 of the latch arm.

When the mechanism 29^a is in the prepared position corresponding to that of the mechanism 29 in Figure 2 the heavier upper end portion 61 of the latch arm will tend to drop downwardly or toward the front of the plate 48, thus swinging the lower portion 58 in position across the bill 57. Consequently, when the crank 26^a is swung around clockwise to bring the trip finger into contact with the rear edge 56 of the trigger 55 the trigger will be held by the latch arm against oscillation, and the crank and escapement mechanism will be operatively coupled together until the mechanism is swung down to approximately the position shown in Figure 6. Upon approaching this last position, the trip arm will enter the recess 53 and will stop the forward movement of the upper end portion of the latch arm, causing the latter to oscillate so as to re-

lease the bill 57, thus permitting the trigger to be swung forwardly and upwardly out of the way and out of contact with the trip finger. This permits the continued clockwise turning of the crank handle.

In the embodiment of the invention shown in Figures 7 and 8 the plate body is generally designated by the reference character 1^b and the crank shaft upon which the driving wheel and crank are mounted is indicated by the reference character 24^b but the said wheel and handle have not been shown. Only the essential parts of the escapement mechanism have been illustrated in these figures and in the embodiments shown in the subsequent figures as it is believed that the association and operation of these parts with the other parts of the cutting implement will be well understood from the description given in connection with the embodiment shown in Figures 1 to 6 inclusive. The bearing sleeve encircling the crank shaft 24^b is indicated by the reference character 23^b, and the sleeve to which the eccentric wheel, not shown, is coupled is indicated by the character 20^b.

In the embodiment of the escapement shown in Figures 7 and 8 the escapement is indicated as a whole by the reference character 29^b, and it comprises the plate 62 which has an opening 63 through which the shaft 24^b and bearing sleeve 23^b extend. At its top edge is the inwardly extending flange 63', with the inner edge of which is joined the downwardly extending ear 64 which is secured to the eccentric wheel sleeve 20^b in the same manner as the ear 35 is shown secured in Figure 1 to the corresponding sleeve 20. Thus, it will be seen that upon turning the plate 62 around the axis of the shaft 24^b the desired turning movement will be given to the eccentric wheel sleeve 20^b.

The top flange 63' is continued along the back edge of the plate 62 forming the back flange 65 which terminates near the bottom edge of the plate, which bottom edge is slightly arcuate, as shown in Figure 8.

Adjacent the bottom of the plate and near the back flange 65 the plate has secured thereto the pivot stud 66 upon which is pivotally mounted the forwardly and downwardly extending trigger 67, the lower end of which projects beyond the lower edge of the plate and has the front and rear oblique contact edges 68 which are engaged by the crank handle carried trip finger, not shown. The lower end portion of the trigger is disposed, when the escapement mechanism is in the release position where the handle carried trip finger may oscillate the trigger so as to escape therefrom, slightly forwardly with respect to the vertical center of the implement so that the rear contact edge 68 extends across the line of the vertical center. The trigger has formed integral therewith the upwardly extending arm 69 which, when the trigger is in the position just stated, is in contact with the bearing sleeve 23^b, as shown in Figure 8.

Forwardly from the arm 69 the plate 62 carries, adjacent its top, the pivot stud 70 upon which is pivotally mounted the bell crank shaped latch 71 which has the relatively long downwardly extending leg 72 and the rearwardly extending leg 73 which terminates in the down-turned hook bill 74. This hook bill is adapted to engage the back edge of the arm 69 which forms a part of the trigger and is caused to swing downwardly for this purpose by the longer leg 72, when the escapement is oscillated to a

position corresponding to the position of the escapement 29 in Figure 2 so as to prepare the implement to receive a can. Thus, the latch and the arm of the trigger are coupled together so that the crank handle carried trip finger, not shown, when brought into engagement with the back contact edge 68 of the trigger will force the escapement mechanism to swing downwardly and forwardly.

The numeral 47^b designates a trip pin or arm which is secured to the body plate 1^b in the path of movement of the end of the latch leg 72. Thus, it will be seen that when the escapement mechanism is swung downwardly and forwardly this leg 72 will be brought into engagement with this trip arm so as to oscillate the latch and disengage the bill 74 from the arm 69, thus springing the trigger to oscillate forwardly to be disengaged from the crank handle.

In the embodiment of the invention illustrated in Figures 9 and 10 the body plate is indicated generally by the numeral 1^c, while the bearing sleeve of the crank handle shaft is indicated by the reference character 23^c, the crank handle supporting shaft being designated 24^c, but the crank handle which it supports not being shown. The reference character 20^c designates the sleeve which is coupled with the eccentric wheel, not shown.

The escapement is indicated generally by the reference character 29^c and this comprises the plate body 75 which, at its upper end, has the inwardly extending top flange 76 which merges with the ear 77 through which the sleeve 23^c freely extends and which is secured to the bearing sleeve 20^c for the purpose of effecting the turning thereof. The bottom edge of the plate 75 is arcuate as shown and the front edge has the inwardly extending flange 78 extending part way down from the top edge of the plate while the back edge has the longer inwardly extending back flange 79 which extends from the top of the plate to the arcuate bottom edge.

At a substantial distance above the bottom edge of the plate 75 there is secured the pivot stud 80 upon which is pivotally mounted the trigger 81 which extends downwardly beyond the lower edge of the plate and which, at its lower end, is bent to extend slightly forwardly so that the lower end will be in line with the shaft 24^c, as shown, when the escapement mechanism is hanging in the position which it assumes when the cutter of the device and the driving wheel have been moved together. The front and rear edges of the portion of the trigger which extends beyond the lower edge of the plate 75 are slightly obliquely disposed, as indicated at 82, to be engaged squarely by the faces of the crank handle carried finger, not shown, in the clockwise and counterclockwise rotation of the handle.

The numeral 83 generally designates a snap link which comprises an upper substantially triangular plate portion 84 and a slightly arcuate lower portion 85. The plate portion 84 is pivotally connected at one point of the angle, by the pivot stud 86, with the plate 75 adjacent the top and forward edges thereof. At the rear lower corner of this triangular plate a pivot stud 87 couples one end of the snap link portion 85 therewith, while the other end of this link portion is pivotally coupled, as indicated at 88, with the trigger 81, below the pivot 80 therefor. It will be seen that the construction of the snap link 83 which connects the trigger below its

pivot with the forward upper corner of the plate 75, is such that when the escapement mechanism is hanging in the manner shown in Figure 10, the forward side of the triangular plate portion 84 will be substantially vertical and the pivot 87 will be slightly in advance of the line connecting the centers of the pivots 86 and 88. The flange 78 prevents the portion 84 swinging forwardly beyond a desired position.

Secured to the body plate 1^c in a position to be passed over by the flange 78 of the escapement plate 75 is a trip arm 89 which extends laterally into the path of movement of the plate portion 84 of the snap link.

When the form of the mechanism shown in Figures 9 and 10 is in prepared position, corresponding to the position of the former embodiment 29 shown in Figure 2, the snap link 83 will tend, by gravity, to straighten out so as to maintain the lower end of the trigger 81 in position to extend below the lower edge of the plate 75 and thus when the crank handle, not shown, is brought around in a clockwise direction to engage the trip finger, not shown, carried thereby with the back edge 82 of the trigger, the trigger will be held against oscillation so that the escapement mechanism may, as a whole, be turned to turn the eccentric wheel which is coupled with the sleeve 20^c. When the limit of downward movement of the escapement mechanism is reached the trip arm 89 will engage and stop further forward movement of the plate 84, thus causing the snap link to break and permitting the trigger to swing upwardly and out of engagement with the handle carried trip finger, thus freeing the latter and permitting the handle to be further turned to complete the clockwise rotation thereof.

In the embodiment of the invention shown in Figures 11 and 12, the body plate is indicated generally by the numeral 1^d, while the bearing sleeve for the crank handle supporting shaft is indicated by the reference character 23^d, and the shaft is indicated by the character 24^d, the crank handle not being shown. The character 20^d designates the supporting sleeve for the eccentric wheel, not shown, which sleeve has the escapement mechanism coupled thereto.

The escapement mechanism as shown in Figures 11 and 12 is indicated generally by the character 29^d and comprises the plate body 90 having at its top edge the inwardly extending flange 91 which merges with the inwardly extending back edge flange 92 which extends downwardly to the arcuate lower edge of the plate 90, as shown in Figure 12. The plate 90 has the central opening 93 through which extends the sleeve 23^d and the shaft 24^d and extending downwardly from the inner edge of the flange 91 is the ear 94 which freely encircles the sleeve 23^d but is secured to the sleeve 20^d for the purpose of imparting rotation thereto.

Adjacent the back flange 92 and near the bottom edge of the plate 90 is secured a pivot stud 95 to which is pivotally attached the forwardly and downwardly extending trigger 96, the lower end of which is disposed directly beneath the shaft 24^d and projects below the arcuate lower edge of the plate 90, as shown in Figure 12. This trigger, like the ones of the other embodiments, has the forward and rear obliquely directed contact edges 97 for engagement by the trip finger, not shown, which is carried by the handle, not shown, of the implement upon clockwise and counter-clockwise rotation thereof.

Integrally connected with the trigger 96 at the pivot is the upwardly and forwardly extending arm 98 which has the downwardly curving terminal portion 99 which extends over the shaft and sleeve 24^d and 23^d, respectively, and terminates near the forward edge of the plate 90.

The numeral 100 generally designates a snap link which has a portion 101 pivotally attached at one end to the terminal portion 99 of the arm 98, by the pivot stud 102. This portion 101 of the snap link hangs downwardly, as shown in Figure 12, or extends substantially parallel with the adjacent side edge of the plate 90, when the end of the trigger 96 is projecting beyond the arcuate edge of the plate. Pivotally connected by the stud 103 with the lower end of the link portion 101, is a shorter link portion 104 which extends upwardly and has its upper end pivotally attached by the pivot stud 105, to the plate 90. The link portion 104 is, as shown in Figure 11, in the plane of the terminal portion 99 and the pivot 105 connecting the link portion 104 with the plate 90 is rotated substantially midway between the ends of the link portion 101 and is slightly rearwardly out of line with and between the pivots 102 and 103. Thus, the accidental breaking of the snap link when force is applied to either side of the projecting end of the trigger 96 is prevented until a rearward thrust is applied to the joint of the snap link, at 103, to force this joint rearwardly as the escapement mechanism is swung forwardly.

The desired rearward thrust to the joint of the snap link is obtained through the action of the trip arm 106 which is carried by the body plate 1^e, as shown in Figure 11, so as to be in the path of movement of the joint of the snap link as the latter is swung forwardly. The accidental breaking of the snap link is prevented by the provision of a stop finger 107 on the edge of the plate 90 which extends inwardly across the two portions of the link, as shown in Figure 11.

From the foregoing it is believed that it will be readily apparent that the escapement just described, when in prepared position for operation, will be disposed at an angle rearwardly from the body 1^e like the escapement 29 of Figure 2 so that when the implement handle is turned clockwise the trip finger, not shown, will engage the rear contact edge 91 of the trigger and force the escapement mechanism to swing downwardly and forwardly. When it has moved to its limit the joint of the snap link will engage against and will be stopped in its forward movement by the trip arm 106, thus forcing the joint to swing rearwardly under the pivot 105 and releasing the trigger so that the latter will oscillate forwardly and upwardly away from and out of connection with the crank handle carried trip finger.

Figures 13 to 20 inclusive illustrate two hand supported types of rotary can openers constructed in accordance with my invention and showing improved embodiments of escapement mechanism for operating or shifting the driving wheel relative to the can head piercing cutter.

In the form of the hand supported tool illustrated in Figures 13 to 18 inclusive the body plate is indicated generally by the reference 1^e. At its upper end this body plate has the laterally turned head portion 108 which, as shown best in Figure 16, is of reduced width and merges with the downwardly directed knife 109, the blade or cutting edge 110 of which is directed obliquely

across the plate and is in spaced relation therewith.

The lower end of the plate 1^e has the laterally turned foot portion 111 which engages against the side of a can to maintain the same in proper parallel relation with the body plate while applying the device and cutting out the can head.

The upper part of the plate body has formed therein the relatively short longitudinally extending guide opening 112 and through this opening extends the shaft 113, the diameter of which is substantially equal to the inside diameter of the opening in which the shaft turns and slides.

The shaft 113 has secured to the end adjacent 15 the blade 110, the toothed driving wheel 114 which is disposed in a plane between the blade and the body 1^e, while upon the other or outer end of the shaft is secured the handle 115 which is formed at the inner side or adjacent to the 20 pivot shoulders 116. These shoulders correspond to and perform the same function as the trip finger 27 of the implement shown in Figures 1 to 4 inclusive.

25 Enclosing the upper part of the body plate 1^e from the rear or back edge thereof is an oscillating yoke which is indicated generally by the numeral 117. As is best seen in Figure 16, this yoke comprises an outer arm 118 and an inner arm in spaced parallel relation with the outer arm, as indicated at 119, and an intermediate web portion 120 which connects the arms and extends across the rear edge of the plate 1^e in spaced relation therewith. The two arms of 30 this yoke are suitably apertured for the passage therethrough of the shaft 113, the arm 119 being disposed between the driving wheel 114 and the plate body 1^e, and the yoke is free to oscillate upon the shaft.

40 The yoke arm 119 has integrally connected therewith and extending downwardly from the bottom edge thereof, a rigid ear 121 which, together with the yoke, forms an element of a thrust mechanism by which, upon the forcible oscillation of the yoke in one direction, the yoke will be made to move toward the head 108 so as to raise the driving wheel relatively to the cutting blade. The other element of this thrust means comprises the link 122 which is pivotally 45 coupled at one end by the stud 123, with the ear 121, while its other end is pivotally secured to the lower part of the body plate by the pivot stud 124, an end of which is fixed to the body plate, as is clearly shown in Figure 17. The pivot stud 124 is substantially in line lengthwise of the body plate with the center of the opening 112 and of the shaft 113 so that when the yoke is in the position where it extends substantially perpendicular to the length of the body plate, the link and ear will be parallel, as shown in Figure 14, and the driving wheel 114 will be in its uppermost or raised position or, in other words, in position to rotate a can to effect the cutting out 50 of the head thereof.

65 The desired oscillation of the yoke to effect the raising and lowering of the driving wheel upon clockwise and counterclockwise turning of the handle 115, is effected by the cooperative action of the shoulders 116 and two oscillating members, one of which is in the form of a bellcrank element, as indicated generally by the numeral 70 125, while the other is in the form of a triple eared coupler, indicated generally by the numeral 126.

The bellcrank element is pivotally attached by

the pivot stud 127 to the arm 118 of the yoke, slightly above and in front of the shaft 113, as shown in Figure 13, and has a latching arm 128 which extends across the shaft toward the rear of the implement and a trip arm 129 which extends downwardly across the front of the shaft 113 and beyond the lower edge of the arm 118.

The coupler is pivotally secured to the arm 118, rearwardly of the shaft 113 and slightly below the same, as shown in Figure 13, and this coupler has the upwardly extending and downwardly extending ears 130 and 131, respectively, and the forwardly extending intermediate ear 132 which, as best shown in Figure 16, is extended outwardly slightly so as to be disposed in the path of rotary movement of the handle trip shoulders 116.

The lower ear 131 of the coupler extends slightly below the lower edge of the yoke arm 118 and adjacent this lower ear, the arm 118 carries the outwardly extending stop 133 which limits the clockwise turning of the coupler.

The forward end of the yoke arm 118 carries the outwardly directed stop 134 which is in the path of movement of the trip arm 129 and below this stop the plate 110 carries the two oppositely directed stops 135 and 136, the first of which is substantially in line with the joint between the ear 121 and the link 122, to limit the movement of this joint while the second stop is in the line with the lower end of the arm 129.

In the operation of the opener of Figures 13 to 18 inclusive, if, at the start, the parts are in the position shown in Figures 13 and 14, the user turns the handle 115 counterclockwise, thus bringing one of the trip shoulders 116 around against the under side of the intermediate ear 132 of the coupler. This will tend to swing the coupler so as to bring the ear 131 against the stop 133 which is carried by the outer arm of the yoke and, since further independent rotation cannot then be given the handle, the handle and the yoke will be oscillated together in a counterclockwise direction and break the linkage connection between the yoke and the fixed pivot 124. This will permit the shaft 113 to drop down in the opening 112 so that the driving roller will be properly spaced with respect to the cutting edge 110 to receive the flange of a can.

After the can flange has been introduced between the driving roller and the point of the cutting blade so that such blade point will be directed toward the head of the can upon the inner side of the flange, clockwise rotation is imparted to the handle 115, thus bringing one of the shoulders 116 around against the top of the intermediate ear 132 of the coupler. When the yoke was oscillated in the manner previously described, it will be seen that the pivot 127 for the bellcrank is swung down and toward the under side of the shaft 113, and the trip arm 129 of the bellcrank tends to swing by gravity to a vertical position, thereby lowering the point of the latch arm 128 to position in front of the upper ear 130 of the coupler. Consequently, when the stated clockwise rotation is given to the handle and one of the shoulders 116 is brought into contact with the top of the intermediate ear 132 the coupler will be held against oscillation and, therefore, further turning movement of the handle independently of the yoke cannot occur. This will cause the yoke to be turned with the handle until the yoke is brought back to the horizontal position in which it is shown in Figure 13, thereby straightening the linkage mechanism and forcing the

feed roller upwardly to the position shown in Figure 14. Just before this final position of the can feed or driving roller is reached the trip arm 129 will be brought into contact with the stop 136, thereby oscillating the bellcrank and lifting the latch arm 128 out of engagement with the upper ear 130 and freeing the coupler for oscillation. Continued clockwise turning may then be given the handle as the shoulder which had engaged the top of the intermediate ear 132 will then be free to move down past the intermediate ear.

In the form of the invention illustrated in Figures 19 and 20 a somewhat similar escapement mechanism is employed. In this form of the invention 15 the body plate is indicated generally by the reference 11 and the lower end of this plate is provided with the inwardly directed foot 137 for engagement against the side of a can while the top is turned to form the head 138 which merges with the knife 139.

This body plate 11 is provided with a longitudinal opening, not shown, corresponding to the opening 112 shown in Figure 17, and through such opening extends a shaft 140, upon the outer end 25 of which is carried the handle 141, while the inner end carries a toothed driving wheel shown in dotted outline in Figure 19, and indicated by the numeral 142.

The numeral 143 generally designates a yoke 30 corresponding to the yoke 117. This yoke has the inner and outer legs 144 and 145, respectively, which are connected by the web 146 and between the legs the body 11 is received, as shown in Figure 19. The inner leg 144 is operatively coupled 35 with the plate body 11 by a linkage, not shown, like that shown in Figures 14 and 18. The operation will, it is believed, be readily understood without the necessity of illustrating such linkage connection between the leg 144 and the plate body.

40 The handle shaft 140 passes through the two legs of the yoke and is freely rotatable independently thereof.

The outer leg 145 is extended at its forward end, 45 as indicated at 147, beyond the forward edge of the body plate and has pivotally attached thereto, at an elevation below that of the shaft 140, the bellcrank 148. The pivot stud for the bellcrank is indicated by the numeral 149 and, as shown, this crank has one arm 150 which extends rearwardly and carries a roller 151, while the other arm of the bellcrank, which is indicated by the numeral 152, extends downwardly as shown in Figure 20.

55 The inner part of the handle 141 is formed to provide the two oppositely disposed trip shoulders 153 and the roller 151 is normally disposed in the path of rotary movement of these shoulders to be engaged by one or the other when the handle is given clockwise or counterclockwise rotation.

60 The forward edge of the body plate has the forwardly extending portion 154 which carries a laterally directed stop 155 which is disposed forwardly of and in the path of movement of the depending crank arm 152 so that the forward swinging motion of this arm is limited.

Carried by the outer arm 145, at its lower edge, is a movement limiting stop 156 against the upper side of which the roller 151 normally bears.

65 When the yoke 143 is horizontal, as shown in Figure 20, the can rim engaging driving wheel 142 is in its raised position with respect to the knife 139. In order to adjust the device for the insertion of a can rim, counterclockwise turning motion is given the handle 141 so as to bring one

of the shoulders 153 around against the top of the roller 151, and since the roller is prevented from swinging downward by the stop 156 it will be readily seen that the turning motion of the handle will be imparted to the yoke, and thus the linkage mechanism, not shown, connecting the yoke with the plate body will be broken in the same manner as illustrated in Figure 18 in connection with the thrust or linkage mechanism of that device, thus permitting the driving roller to be lowered. After the can rim has been placed in position clockwise rotation is given the handle which will bring a shoulder around against the side of the roller 151 and thrust will be imparted to the forward end of the arm 145 below the pivotal center of the shaft, and thus cause the yoke to be oscillated back to horizontal position. As the yoke swings back to this horizontal position, the end of the depending trip arm 152 will be brought into contact with the stop 155, thus causing the bellcrank to swing and the roller 151 to be raised, thereby permitting the shoulder which has been in engagement with it to ride under the roller and swing upwardly, the roller swinging away to the left and the shoulder swinging to the right. Thus, continued rotation may be given to the handle until the full use of the device is completed.

In Figures 21 and 22 there is shown a further embodiment of my can opener structure in which are illustrated an improved bearing unit for the eccentric wheel which is so designed that it may be readily applied or used upon the instruments shown in the preceding figures and in the structures of my prior patents, in place of the spring arms there illustrated, and a modified form of escapement based upon the form illustrated in Figures 11 and 12 of the present application. Details of the eccentric wheel spring supporting unit are set forth in Figures 25 to 27 inclusive, while Figures 23 and 24 illustrate particularly a modified and improved mounting for the can head penetrating and cutting blade.

Figures 28 and 29 illustrate the manner in which the improved spring supported bearing may be employed in association with the toggle escapement illustrated in Figures 12 to 15 of my prior Patent 2,287,442. In Figures 21 to 23 the body of the instrument or body plate is indicated generally by the reference character 18. This plate at its top or head end has the laterally extending portion 157 while adjacent its lower end it is slightly offset to form the shoulder 158. The portion of the body plate below this shoulder has secured thereto the forward end of the supporting bracket or arm 159 which corresponds with the bracket 2 of Figures 1 to 4. The top edge of this bracket is flush with the top of the shoulder, as shown in Figure 21.

The central part of the laterally directed edge of the portion 157 has a recess 160 therein, as shown in Figure 24, and at the inner edge of this recess there is secured to the portion 157, the vertical bracket 161 which has a laterally directed upper end portion 162 which merges with a depending portion 163, the lower edge of which lies within the recess 160. This upstanding unit comprising the parts 161 to 163 forms a support for a cutting blade 164 which is interposed between the parts 161 and 163 and is secured to the part 163 by screws 165. The part 163 is of resilient metal so that the supported blade may have a slight lateral movement with respect to the driving wheel hereinafter described, which lies below the lateral extension 157, as shown in Figure 21.

As is also shown in this figure, the cutting edge 166 of the blade extends below the head portion 157 of the plate.

The body plate 18 has formed therein the vertically extending elongated recess or slot 167 which corresponds with the slot 19 of the structure shown in Figures 1 to 4. Through this slot extends the sleeve 168. This sleeve is of an overall diameter substantially equaling the width of the slot 167 so that it may move vertically therein and also have rotational movement.

Extending through the sleeve 168 is a bearing sleeve 169 and through the bearing sleeve extends a shaft 170 which has secured to the end nearest the blade 164, the toothed can driving wheel 171.

The sleeve 168 extends into and is firmly secured to the eccentric wheel 172, at that end which is nearest the driving wheel 171. As shown in Figure 21, a portion of the end of the sleeve is suitably swaged over to secure it to the eccentric wheel and the lower part of the sleeve is cut square across so as to establish a connection with the eccentric wheel which will prevent relative rotary movement between the same and the sleeve.

The numeral 173 designates the improved resilient or spring bearing unit which is designed for application to the body plate to provide a yieldable support or bearing for the eccentric wheel 172. This unit 173 comprises a plate 174 which is designed to position between the eccentric wheel 172 and the body plate 18 and opposite vertical edges of this plate 174 have the flanges 175 which extend across the edges of the body plate to assist in maintaining the bearing unit plate in position.

At its central portion the bearing unit plate 174 has a vertically extending opening or slot 176 which is of the same dimensions as the slot 167 with which it aligns to receive a portion of the rotatable eccentric sleeve 168, as shown in Figure 21.

The lower edge of the bearing unit plate 174 rests upon the shoulder 158 and formed integral with the side edges of the bearing unit plate at the bottom thereof, are the arms 177 which are in spaced relation with and extend across the front of the plate 174 to form a box in which is retained the corrugated strip spring 178 and the elongated bearing block 179 which rests upon the spring, as shown in Figure 25. The spring rests upon the top edge of the bracket 159 and supports the block 179 beneath and in the plane of the eccentric wheel 172, the edge of which bears against the top edge of the bearing block, as shown in Figure 21. Upon the opposite side of the body plate from the unit 173, is disposed the escapement mechanism which cooperates with the operating handle of the instrument to effect the desired movement of the eccentric wheel and driving wheel relative to the edge of the cutting knife. This escapement mechanism comprises an oscillating plate 180 which is secured to the other end of the eccentric wheel sleeve 168 to turn with this sleeve and with the eccentric wheel. The plate 180 supports below the shaft 170 and to one side of the vertical center of the body plate, a pivot stud 181 upon which is mounted for rocking movement the downwardly extending trigger 182, the lower end of which is disposed directly beneath the shaft 170. This trigger, like those of the other embodiments, has the forward and rear obliquely directed contact edges 183 for engagement by the trip finger 184 which is carried by the crank 185, which in turn

is secured to and supported by the shaft 170. Through the medium of this crank the desired rotary motion is imparted to the rock plate and the eccentric wheel, through the trip mechanism and subsequently to the shaft 170 and the toothed driving wheel 171, after the latter has been raised to shift the can head, not shown, against and cause it to be penetrated by the point of the cutting edge 166 of the knife.

Integrally connected with the trigger 182, at the pivoted end thereof, is the upwardly and forwardly extending arm 186 which terminates in the downwardly curving portion 187, such portion extending over the top of the shaft 170 to the forward edge of the body plate, as shown in Figure 22.

The numeral 188 generally designates a snap link comprising a long portion 189 which is pivotally connected at one end by means of the pivot pin 190, with the free end of the downturned terminal portion 187 of the arm 186, and a short portion 191 which has one end pivotally connected by the pin 192 with the other and lower end of the portion 189. This shorter portion of the snap link extends upwardly and slightly obliquely with respect to the normally vertically disposed portion 189 and is connected by the pivot pin 193 with the rearwardly extending terminal portion 194 of the bracket plate 195 which is secured to the forward edge of the oscillating plate 180.

Secured to the forward edge of the body plate 18 below the bracket plate 195 is a stop finger 196 which projects laterally into the path of movement of the lower end of the portion 189 of the snap link.

From the description of the previously described forms of the invention, particularly that shown in Figures 11 and 12, it will be readily understood that upon rotation of the handle 185 counterclockwise the finger 184 will strike the forward edge 183 of the trigger and cause the plate 180 to oscillate and impart counterclockwise rotation to the eccentric wheel 172 whereby to lower the sleeve 168 and the driving wheel 171 with respect to the cutting edge 166 of the knife.

When the bead at the edge of a can is inserted between the driving wheel and the edge of the knife and clockwise rotation is then given the handle, the finger 184 will be brought around against the opposite edge 183 of the trigger and impart clockwise rotation to the plate 180. As the lower portion of the snap link moves forwardly it will come into contact with the fixed stop finger 196 just as the driving wheel 171 is about to reach the upward limit of its movement. Further oscillation of the plate 180 will force the pivotally joined portions of the snap link to the rear so as to swing the pivot 193 across the pivot 192, thus allowing the snap link to open out and permitting the trigger to swing sufficiently far forwardly for the finger 184 to pass therebeneath. During rising movement of the eccentric wheel 172 the thrust of the wheel will be exerted against the bearing block 179 and any necessary yield will be allowed by the underlying spring.

Necessary lateral movement of the knife 164 is taken care of by the mounting of the knife upon the freely suspended forward portion 163 of the bracket 161.

Figures 28 and 29 show the manner of using the bearing units in conjunction with a toggle link thrust means such as is illustrated in Figures 12 to 16 of my Patent No. 2,287,442.

In this construction the body plate of the implement is indicated generally by the reference character 1^h and the lower link of the toggle is indicated by the reference character 197. The bearing unit is indicated generally by the reference 198 and is secured to the body plate 1^h by the rivet 199 which is connected with and provides the pivot for the lower end of the link 197, as illustrated. As is shown in Figure 28, the link 197 has an aperture for the pivot pin which is slightly elongated to allow for a slight amount of vertical play.

The bearing block box for the unit 198 is indicated generally by the reference character 200, the block being designated 201 and the underlying supporting spring, shown in dotted outline, being designated 202.

The lower end of the link 197 of the toggle bears against the top of the block 201 and thus when the toggle is straightened out to force the driving wheel, not shown, which is supported thereby, upwardly, the thrust is taken by the bearing block and if such thrust should be excessive the underlying spring will yield to prevent damage to the implement.

From the foregoing it is believed that it will be readily apparent that there have been described in connection with the different forms of rotary type can opener here disclosed, several embodiments of a generally novel escapement mechanism which have in common a crank handle carried means engaged by a trigger or releasable holding means whereby there is maintained an operative connection between the handle and an escapement mechanism until a desired relative movement between the can top cutting knife and the can rim driving wheel has been obtained; whereupon the actuation of a trip mechanism releases the coupling between the handle and the holding means, thus permitting continued uninterrupted rotation of the handle until the can top cutting operation is completed. Also, it will be apparent that the means by which the handle holding means is releasably held, is reset automatically by gravity upon the reverse or counterclockwise rotation of the escapement to its set position, by which is meant the position which it assumes when separation is effected between the can rim engaging driving wheel and the cutter preparatory to the placement of a can in position.

I claim:

1. In a can opener having a body carrying a cutter, a rotatable wheel, a rotatable eccentric carrying the wheel for moving the wheel relative to the cutter and a crank for turning the wheel; a mechanism for releasably coupling the crank and eccentric comprising a finger carried by the crank, a body securely coupled with the eccentric to turn therewith on the axis of the crank and the wheel but independently of the crank and wheel, a pivoted trigger carried by the last mentioned body and arranged to be engaged by the finger upon turning of the crank, means for securing the trigger against movement during a period of rotary movement of the last body, and trip means for releasing the trigger for oscillation out of engagement with the finger after a predetermined rotary movement of the last body.

2. In a can opener having a body carrying a cutter, a rotatable eccentric, a rotatable driving wheel carried by the eccentric and moved by and upon rotation of the eccentric relative to the cutter and a crank for turning the wheel; a mechanism for releasably coupling the crank and

eccentric upon turning the crank, comprising a carrier body secured to the eccentric to turn therewith on the turning axis of the crank and wheel but independently of the latter, a trigger pivoted on the carrier body, an oscillatable unit on the carrier body having an active and an inactive position and functioning when in the active position to hold the trigger against oscillation, a means carried by the crank to engage the trigger upon turning the crank to effect simultaneous turning of the eccentric with the crank, and a trip fixed to the first body to engage and oscillate said unit to inactive position for release of the trigger when the eccentric has been turned in one direction to a predetermined position, the trigger when so released disengaging from the crank carried means.

3. In an escapement mechanism for releasably coupling two independently turnable elements supported for turning on a common axis, in which one element carries a coupling finger, a body secured to the other element to turn therewith on said axis, a trigger carried by the body and pivoted to oscillate on an axis paralleling the first axis, said trigger having a normal position in which it is in the path of movement of said finger, an oscillatable unit on the body having an active and an inactive position, the unit when in active position maintaining the trigger against oscillation from its normal position whereby the trigger and finger may be coupled to effect turning of the two elements together, and a trip means arranged to contact said unit when the body has been turned through a predetermined extent and oscillate the unit to inactive position for release of the trigger and its disengagement by swinging from the finger.

4. An escapement as set forth in claim 3, in which said unit constitutes a two-part snap link, the said two parts being pivotally coupled together and one of said parts being pivotally connected with the trigger and the other part being pivotally connected with the body.

5. In an escapement mechanism for releasably coupling two independently turnable elements supported for turning on a common axis, in which one element carries a coupling finger, a plate secured to the other element to turn therewith on said axis, said plate and the said other element having a raised and a hanging position, a trigger pivotally attached to the plate to oscillate on an axis substantially paralleling the first axis and projecting beyond an edge of the plate, said trigger having a normal position in which it is in the path of movement of the finger, a two-part snap link having the parts thereof pivotally coupled together, one of said link parts being pivotally attached to the trigger and the other one of the link parts being pivotally attached to the plate in a plane between the pivotal axis of the trigger and the first axis and to one side of a line passing between said axes, said snap link having an active position in which the parts are substantially aligned to maintain the trigger against oscillation and an inactive position in which the link is broken and the trigger is oscillated inwardly with respect to the adjacent edge of the plate, and a fixed trip means disposed to be engaged by said link when the plate is swung from its raised to its lowered position to effect the breaking of the link.

6. An escapement mechanism as set forth in claim 3, in which said unit comprises a bar pivotally mounted intermediate its ends upon the body and adapted to have one end coupled with

the trigger to maintain the latter against oscillation and engaged adjacent its other end by the trip means for the release of the trigger.

7. An escapement mechanism as set forth in claim 3, wherein said trigger carries an arm, and said unit is substantially in the form of a bell-crank having one leg terminating in a hook adapted to engage across the end of the trigger arm and having its other leg disposed for engagement against the trip means whereby upon actuation of the unit by the trip means the said hook is disengaged from the trigger arm.

8. A rotary type can opener comprising a body plate adapted to be vertically disposed and carrying a can top cutter at its upper end, an eccentric wheel carried by the plate for rotation and carrying a sleeve which is moved vertically simultaneously with such rotation, a driving wheel supported upon the eccentric wheel for turning movement independently thereof, a crank connected with the driving wheel for turning the latter, a plate secured to said sleeve for rotation therewith and suspended between the body plate and crank, a coupling finger carried upon the side of the crank adjacent the second mentioned plate, a trigger pivotally mounted upon the second plate to extend below the bottom edge thereof in the path of movement of the finger, a two-part trip link connected between the trigger and second plate, said trip link having an active position in which the two parts are related in a manner to maintain the trigger against oscillation and having an inactive position in which the two parts are relatively shifted for oscillation of the trigger out of engagement with said finger, and a fixed trip means carried by the body plate in position to engage and break the snap link when the second mentioned plate is oscillated for the turning of the eccentric wheel and the raising of the driving wheel to a predetermined position.

9. A rotary type can opener as set forth in claim 8, wherein said snap link is pivotally attached to the second plate at the side of a line passing between the rotary axis for the wheels and the rotary axis for the trigger, nearest to said trip means whereby upon oscillation of the second plate away from the trip means the snap link will be straightened by gravity to secure the trigger against oscillation.

10. A rotary type can opener as set forth in claim 8, in which the snap link is pivotally attached to the second plate upon the side of a line passing through the rotary axes for the wheels and for the trigger, nearest the trip means and in which the portion of the snap link which is pivotally attached to the second plate is of substantially triangular form and has the bulk of its width upon the side of the pivot between the two portions nearest the trip means whereby, upon oscillation of the second plate in a direction to effect turning of the eccentric wheel for the lowering of the driving wheel from the cutting means, the snap link portions will shift by gravity to substantially align the pivots thereof and to lock the trigger against oscillation.

11. A rotary type can opener comprising a plate body designed to be vertically disposed and carrying a cutter at its upper end, a rotary cam wheel supported upon the body, a sleeve carried by the cam wheel and adapted to be moved vertically of the body upon rotation of the wheel, a driving wheel rotatably supported by the sleeve for turning independently thereof, a crank oper-

atively coupled with the driving wheel for turning the latter, a coupling finger carried by the crank upon the side thereof nearest the plate body, a plate secured to said sleeve for turning therewith and suspended between the first plate and the crank, the second plate having a rearwardly swung position in which the cam is turned to shift the driving wheel away from the cutter and a hanging position in which the cam is turned to shift the driving wheel toward the cutter, a trigger pivotally attached to the second plate to project below the lower edge thereof in the path of movement of the finger, said trigger having a forwardly directed bill, a bar pivotally secured intermediate its ends to the second plate forwardly thereon with respect to the trigger pivot and normally extending lengthwise of the second plate, the bar having a lower end portion adapted to engage said bill to maintain the trigger against oscillation, and a trip means secured to the plate body and arranged to engage the upper end of the bar upon the swinging of the second plate in a direction to turn the cam wheel for the raising of the driving wheel relative to the cutter, to oscillate the bar and disengage the trigger for swinging movement out of engagement with the coupling finger.

12. A rotary type can opener comprising a plate body designed to be vertically disposed and carrying a cutter at its upper end, a rotary cam wheel supported upon the body, a sleeve carried by the cam wheel and adapted to be moved vertically of the body upon rotation of the wheel, a driving wheel rotatably supported by the sleeve for turning independently thereof, a crank operatively coupled with the driving wheel for turning the latter, a coupling finger carried by the crank upon the side thereof nearest the plate body, a plate secured to said sleeve for turning therewith and suspended between the first plate and the crank, the second plate having a rearwardly swung position in which the cam is turned to shift the driving wheel away from the cutter and a hanging position in which the cam is turned to shift the driving wheel toward the cutter, a trigger pivotally attached to the second plate at the rear of the vertical center of the axis of turning for the wheel and extending beyond the lower edge of the second plate in the path of movement of the finger, an arm integral with the trigger and extending away from said lower edge of the second plate across the turning axis for the wheel, securing means for said trigger in the form of a bell-crank pivotally attached to the second plate upon the opposite side of the axes for the wheels from the pivot for the trigger, said bell-crank having one leg extending rearwardly and terminating in a hook adapted to engage across the end of the trigger arm and a second leg extending downwardly, and a trip means carried by the plate body and adapted to engage said second leg to free the hook from the arm upon oscillation of the second plate in a direction to turn the cam wheel for the raising of the driving wheel.

13. A rotary type can opener comprising a plate body designed to be vertically disposed and carrying a cutter at its upper end, a rotary cam wheel supported upon the body, a sleeve carried by the cam wheel and adapted to be moved vertically of the body upon rotation of the wheel, a driving wheel rotatably supported by the sleeve for turning independently thereof, a crank operatively coupled with the driving wheel for turning the latter, a coupling finger carried by the

crank upon the side thereof nearest the plate body, a plate secured to said sleeve for turning therewith and suspended between the first plate and the crank, the second plate having a rearwardly swung position in which the cam is turned to shift the driving wheel away from the cutter and a hanging position in which the cam is turned to shift the driving wheel toward the cutter, a trigger pivotally attached to the second plate and extending beyond the lower edge thereof into the path of movement of said finger, an arm carried by the trigger and extending upwardly and forwardly and terminating in a downwardly curved terminal portion, said curved portion extending over the top of the axial centers for the wheels, a two-part snap link having an end pivotally attached to the terminal of said arm and having its other end pivotally attached to the second plate, the parts of the snap link being pivotally coupled together and in side by side relation when the second plate is hanging downwardly whereby the pivot for the said other end is disposed above the pivotal connection between the parts of the snap link, and a trip member carried by the plate body for engagement by the coupled ends of the snap link parts when the second plate has been swung to a position to turn the cam wheel and raise the driving wheel whereby to break the snap links and permit said trigger to oscillate out of engagement with the finger.

14. A rotary type can opener, comprising a plate carrying a cutter and having a longitudinal opening terminating at one end adjacent the cutter, a rotatable shaft extending through the opening to turn and move longitudinally therein, a can rim engaging driving wheel attached to and turning with said shaft, an escapement body supported for oscillation coaxially with the shaft, a thrust means operatively coupled between the escapement body and the plate and supporting the shaft to shift the shaft in the opening for movement of the driving wheel relative to the cutter upon oscillation of the escapement body, a handle connected with the shaft, a trip means carried by the handle adjacent the escapement body, and an escapement mechanism carried by the escapement body and having a cooperating part on the plate for effecting an operative coupling between the trip means and the escapement body and oscillation of the escapement body and actuation of the thrust means to separate the driving wheel and cutter upon the turning of the handle in one direction, and for effecting an operative coupling between the trip means and the escapement body and oscillation of the escapement body and actuation of the thrust means to move the driving wheel and cutter together upon the turning of the handle in the opposite direction, the escapement mechanism coacting with said cooperating part on the plate to uncouple from the trip means when the wheel and cutter have been brought to a predetermined relative position to allow continuous free turning of the handle.

15. A rotary type can opener comprising a plate carrying a cutter and having a longitudinal opening therein, said opening terminating at one end adjacent the cutter, a rotatable shaft extending through the opening to turn and move longitudinally therein, a can flange engaging driving wheel operatively coupled with the shaft adjacent the cutter, an escapement body supported by and for oscillation coaxially with said shaft, a thrust means operatively connected with and between the escapement body and the plate and support-

ing the shaft to shift the shaft in the opening to effect movement of the driving wheel relative to the cutter upon oscillation of the escapement body, a handle connected to the shaft, a trip means connected with the handle adjacent to the escapement body, a member oscillatably supported upon the escapement body between the handle and the body and having a portion positioned for engagement by the handle trip means upon oscillation of the handle in either clockwise or counterclockwise direction, means carried by the escapement body for holding the member against oscillation when the trip means is moved into contact with the member portion upon rotation of the handle in one direction whereby to impart oscillation to the escapement body to effect actuation of the thrust means and shifting of the driving wheel away from the cutter, a shiftable latching means carried by the escapement body functioning to secure said member against reverse oscillation when the handle trip means is brought into engagement with the opposite side of the member portion upon rotating the handle in the opposite direction whereby to impart reverse oscillation to the escapement body and actuation of the thrust means to move the driving wheel and cutter together, and means carried by the plate for engaging and shifting the releasable holding means for the member when the cutter and wheel have been moved together to a predetermined position, for the release of the oscillatable member to permit continued turning of the handle in the said opposite direction.

16. A rotary can opener comprising a plate carrying a cutter and having a longitudinal opening therein terminating at one end adjacent the cutter, a rotatable shaft extending through the opening to turn and move longitudinally therein, a drive wheel connected with said shaft and disposed adjacent the cutter, an escapement body supported by the shaft for oscillation coaxially therewith and independently thereof, a thrust means operatively coupled with the escapement body and with the plate and supporting the shaft to shift the shaft in the opening and move the driving wheel relative to the cutter upon oscillation of the escapement body, a handle connected to the shaft, a trip means carried by the handle between the handle and the escapement body, a member pivoted to the escapement body and carrying an extended portion in the path of movement of the trip means, means limiting oscillation of the member in one direction whereby upon turning the handle in one direction to bring the trip means against one side of said extended portion oscillation in one direction will be transmitted to the escapement body to actuate the thrust means in a direction to separate the driving wheel and cutter, a gravity actuated latching means which operates upon oscillation of the escapement body in the said one direction to secure the member against oscillation in the reverse direction whereby turning the handle in the opposite direction will bring the trip means against the opposite side of the extended portion and effect reverse oscillation of the escapement body to actuate the thrust means for movement of the wheel and cutter together, and means carried by the plate for shifting said latching means for release of said member as the wheel and cutter are moved together whereby the member may turn to free the trip means from the extended portion.

17. A rotary can opener comprising an elongated body plate carrying a cutter at one end

and having a longitudinal opening terminating at one end adjacent the cutter, a rotatable shaft extending through the opening to turn and move longitudinally therein, a driving wheel operatively connected with the shaft adjacent the cutter, an escapement plate disposed across one side of the body and having said shaft freely extended therethrough for rotation independently thereof, a thrust means operatively connected between the escapement plate and the body whereby oscillation of the escapement plate will effect the shifting of the shaft and driving wheel relative to the cutter, a handle connected with the shaft upon the side of the escapement plate remote from the body, a trip means carried by the handle for movement around the axis of the shaft, a coupler member supported on the escapement plate between the same and the handle and having opposite upper and lower ears and an intermediate ear, the intermediate ear being disposed in the path of movement of the trip means, means carried by the escapement plate adjacent the lower ear for limiting oscillation of the coupler member in one direction whereby upon counterclockwise turning of the handle the trip means will engage the intermediate ear to effect coupling of the handle and escapement plate together and actuation of the thrust means to separate the wheel and cutter, a bellcrank pivotally attached to the escapement plate and having a latch arm movable into engagement with the upper ear to hold the coupler member against oscillation and a downwardly extending trip arm, and means carried by the body plate for engagement by the trip arm upon reverse oscillation of the escapement plate during clockwise rotation of the handle with the trip means engaging the opposite side of the intermediate ear, to effect disengagement of the latch arm from the upper ear and the freeing of the handle from the intermediate ear to permit continued clockwise turning of the handle.

18. A rotary can opener comprising an elongated body plate carrying a cutter at one end and having a longitudinal opening therein terminating at one end adjacent the cutter, a rotatable shaft extending through the opening to turn and move longitudinally therein, a driving wheel operatively connected with the shaft adjacent the cutter, an escapement plate disposed transversely of the body plate and having the shaft freely extended therethrough for turning independently of the shaft upon the axis of the shaft, a thrust means operatively coupled with the escapement plate and with the body to effect relative movement between the cutter and wheel upon oscillation of the escapement plate, a handle connected with the shaft, a trip means carried by the handle, a bellcrank member pivotally attached to the escapement plate below and to one side of the shaft and having a hanging arm and a trip arm disposed in the path of movement of the trip means, means carried by the escapement plate beneath the trip arm for limiting the downward movement thereof whereby the trip arm will be engaged by the trip means upon clockwise and counterclockwise turning of the handle to limit such turning whereby clockwise and counterclockwise oscillation will be given the escapement plate to effect through the thrust means the desired relative movement between the wheel and cutter, and means carried by the body plate for engagement with the depending arm of the bellcrank upon a predetermined clockwise oscillation of the escapement plate to effect the shifting of

the trip arm away from and out of contact with the trip means whereby continued clockwise turning of the handle is facilitated.

19. In a can opener having a body carrying a cutter blade, a rotatable can rim engaging driving wheel, a shiftable thrust means operatively coupled with the driving wheel, a crank actuated mechanism coupled with said thrust means for actuating the same to effect movement of the driving wheel relative to said blade, and a bearing unit for said thrust means comprising means coupled with the first body and forming a box-like receptacle beneath the thrust means, a spring disposed within and maintained in operative position by said receptacle, and a bearing body disposed in the receptacle and supported upon said spring and having said thrust means in operative engagement with the top thereof.

20. In a can opener having a flat body plate, a rotatable can rim engaging driving wheel, 20

thrust means for effecting movement of the wheel relative to a cutter, means for actuating the thrust means and turning the wheel, a cutter head comprising a lateral extension at one end of the body and adjacent the wheel, said extension having an edge remote from the body plate in which is formed a deep recess, a member integral with the extension at the inner edge of the recess and comprising upwardly, laterally and downwardly extending portions, said downwardly extending portion being disposed in the recess and adapted for resilient movement therein relative to the upwardly extending portion, and a cutting blade secured to the downwardly extending portion between the latter and the upwardly extending portion and having a cutting edge extending down through the recess and positioned at one side of the plane of movement of the driving wheel for coaction therewith.

ROBERT E. McLEAN.
